UNITED STATES PATENT OFFICE.

EDWARD C. CURREY, OF MITCHELL, DAKOTA TERRITORY, ASSIGNOR OF ONE-HALF TO ALPHONSO W. HAGER, OF SAME PLACE.

EVENER-SPRING FOR WHIFFLETREES.

SPECIFICATION forming part of Letters Patent No. 319,961, dated June 16, 1885.

Application filed March 28, 1885. (No model.)

To all whom it may concern:

Be it known that I, EDWARD C. CURREY, a citizen of the United States, residing at Mitchell, in the county of Davison and Territory of Dakota, have invented a new and useful Machine or Mechanical Device known as a Whiffletree-Evener Spring, of which the following is a specification.

My invention relates to draft-equalizers; 10 and it consists in a spiral spring secured to a metallic frame above or below the vehicle pole or tongue, or attached to a harrow or other machine in any suitable way.

It further consists in details of construction 15 and operation of the several parts, as will be hereinafter more fully set forth in the specification, and pointed out in the accompanying drawings.

The object of the device is to reduce the 20 shock or jerk upon the shoulders of animals when engaged at work and equalize the strain. These objects are attained by the device shown in the accompanying drawings, in which—

Figure 1 is a longitudinal vertical section 25 of my device; Fig. 2, a top view of the iron eye-plate attached to the front side of the whiffletree-evener to receive the evener-bolt; Fig. 3, a vertical section of the rear head-plate and the supporting tongue or pole; and 30 Fig. 4, a vertical section of the device for attachment to plows, harrows, &c.

Referring more particularly to the drawings, in Fig. 1 I have shown the spiral spring E in position and held in place by a plate, 35 C, having a continuous slot in which the bolt B and head-plate I move. A similar slot is provided in the lower plate or tongue or pole. The bolt-socket attached to the front of the evener is round on its front face and bears on 40 the head of plate I on its center all the time, and thus insures an even and direct bearing on the spring. The evener pivots on this bolt which is in the socket having a round front, and it is evident there can be no other than a center bearing, whichever end of the evener is ahead. 45 I thus insure the bolt and head-plate moving in a straight line forward and backward, as well as assisting to keep the braces F G in position.

I also avoid a difficulty experienced in other forms of eveners, in which if either end of the 50 evener is drawn one foot ahead, (as is very commonly the case,) the spring would break off; or if it did not at first break it would become so twisted that it would stay in place but a short time. A guard, N, holds the spring 55 in position along the sides. A buffer, L, of rubber, gutta-percha, or other suitable material, serves to take up the shock and strain caused by the evener A after the compression of the spring E. I may use a metallic spring 60 for a buffer instead of the rubber, &c., just described.

When the device is attached to plows, harrows, and other implements of like character, or horse-cars, where no tongue or pole is used, 65 I attach the evener A to the rod Q, Fig. 4, which passes lengthwise through the spring E and is fixed to the head-plate R at the rear end of the spring. Back of this head-plate is a buffer, L, against which the head-plate strikes 70 upon its return after the compression of the spring. The head of rod Q comes in contact with a buffer, X, upon its return movement. By means of the ring T and bolt U, I am enabled to attach the device to cars, harrows, 75 &c. The spring is held in position and moved between the upper and lower plates, Y, and the side plates, Z. These side plates are secured to the end pieces, W.

The device is simple and durable, and can 80 be easily attached to any vehicle or implement and be readily removed therefrom when necessary.

Having thus described my invention, what I claim as new, and desire to secure by Letters 85 Patent, is—

In a draft-equalizer, the combination, with the evener, of the spiral spring, the slotted holding-plate, a bolt and head plate moving in a slot in said holding-plate, the bolt-socket, 90 the end braces, guard, and buffer, substantially as and for the purpose set forth.

EDWARD C. CURREY.
